DENTAL INSTRUMENT

Albert E. Sykes, Berkeley, Calif.

Application February 23, 1946, Serial No. 649,570

8 Claims. (Cl. 32—17)

1

This invention relates to instruments employed in the processes of tooth reconstruction.

An object of the invention is to provide a hand tool particularly adapted to the removal from teeth of temporary cap members employed in taking impressions for permanent jackets, inlays or crowns for the teeth.

A further object of the invention is to provide, in an instrument of the character described, effectively operating tong members for tenaciously gripping a cap member and for maintaining said grip while the cap member is being lifted from a tooth.

Another object of the invention is to provide a simple lever device, for lifting impression caps from teeth, in which a degree of pivotal movement is permitted in the plane of movement of the lever so as to produce a substantially linear lift on the caps regardless of the fact that the immediately adjacent portion of the lever is moving in an arcuate path.

Still another object of the invention is to provide an instrument of the character described which is comparatively compact and which will provide a satisfactory degree of operational visibility when it is in use in a patient's mouth.

Yet another object of the invention is to provide, in an instrument of the character described having opposed tong members relatively movable between positions to grip and to engage a cap member, means under control of the operator for releasably holding said tong members in one of said positions.

The invention possesses other objects and features of advantage, some of which, with the foregoing, will be set forth in the following description of the preferred form of the invention which is illustrated in the drawing accompanying and forming part of the specification. It is to be understood, however, that variations in the showing made by the said drawing and specification may be adopted within the scope of the invention as set forth in the claims.

Referring to the drawing:

Figure 1 is a top plan view of the instrument of my invention.

Figure 2 is a side elevational view of the instrument of my invention showing its application in the removal of a cap from a tooth.

Figure 3 is an enlarged vertical sectional view taken in the plane indicated by the line 3—3 of Figure 2.

Figure 4 is a vertical sectional view taken in the plane indicated by the line 4—4 of Figure 3. The parts are shown in their respective posi-

2

tions when the cap is partially lifted from the tooth.

Figure 5 is a side elevational view of a modified form of the instrument of my invention.

As a part of the procedure in the reconstruction of broken or partially decayed teeth, by providing the latter with a permanent protective jacket, crown or inlay if it is necessary, after the tooth has been prepared for the reception of the repair part, to take an indented impression of the tooth from which the form-fitting part may be patterned. In taking this impression, which is usually done by pressing a wad of plastic material such as wax, gutta percha or other dental impression compound around and to enclose the tooth, extreme care must be exercised in removing the wax with its imprint from the tooth so as to accurately retain the exact size and form of the tooth. Any slight deviation from a linear movement perpendicular to the tooth may result in an impression which is distorted or enlarged and the cap, jacket or inlay subsequently made in part from the impression will not fit properly when applied to the tooth with the result that recalling of the patient and the taking of a subsequent impression is often necessary. It is common practice among many dentists to remove the wad of impression material with the aid of forceps. This procedure is, however, very likely to produce a large proportion of faulty impressions, since the lateral pressure of the forceps jaws on the material, as the wad is separated from the tooth, may be sufficient to cause a decided collapsing of the cavity.

I have provided an instrument, designed for facilitating impression-taking of the character described, which if properly and carefully used, will insure a maximum proportion of acceptable impressions. As will be seen in Figure 3, the tooth 6, in this case to be fitted with a crown or jacket, is enclosed by a tubular cap or shell 1 containing one of the previously mentioned impression compounds 8 which entirely surrounds the tooth. Notches 9 are provided at diametrically opposed positions on the shell 1 and are formed by depressing or displacing inwardly side wall portions of the shell. The instrument, which is engageable with and to lift the shell from the tooth, is composed of the usual hexagon rod of which most dental instruments of this general type are constructed, and comprises a handle portion 11 turned down at one end to form a shank 12 having a flange 13 from which extends in axial alignment with the handle and shank, a stem 14 having a threaded end portion 16, on

which is engaged a nut 17, and an integral axially extending portion bent, preferably rectangularly with respect to the common axis of the handle, shank and stem, to form a stud 18. I provide a pair of cooperative grip members on the lever portion of the instrument above described, each of which comprises a wing 19 provided with an aperture 21 for receiving the stem 14 so that the wing is journaled on and extends radially from the stem. The aperture 21 of each wing is substantially larger in diameter than the stem so that the grip members are free to tilt, to a certain degree, on and in a direction axially of the stem. The respective wings 19, which extend in opposite directions radially of the stem as shown in Figure 2, are each provided with an integral downwardly extending arcuate claw 22 having at its distal end a slightly upturned hook 23 adapted to engage in the transverse plane shoulder of the shell notch 9. Tabs 24, also formed integrally with the wings 19, extend upwardly from the latter in relatively spaced relation and form control elements which, upon being squeezed together will cause the claws 22 to spread apart and release the shell 7. An arcuate notch 26 formed in one of the wings 19, and concentrically with its aperture 21, cooperates with a pin 27 fixed in the other wing to limit the degree of relative recession and approach of the claw hooks 23, and a spring having opposed, radially extending end portions 28 secured in apertures 29 provided in each grip member, serves to normally urge the claws 22 toward each other.

Means is provided, under control of the operator's hand holding or manipulating the instrument, for operating the claws to effect opening or closing thereof. Mounted on and for slidable movement longitudinally of the handle portion 11 is a sleeve 31 provided with forwardly and rearwardly extending fingers 32 and 33 respectively, the former of which has an integral head portion 34 provided with an aperture 36 having angularly related sides 37 converging toward the sleeve 31 and lying adjacent the outer sides of the tabs 24. The rearward extending finger 33 has a loop 38 therein at its junction with the sleeve which performs the dual function of a finger grip and of a spring urging the finger 33 against the side of the handle portion 11. The outer end of the finger 33 is provided with a protuberant portion 39 which, as the sleeve 31 is moved along the handle portion 11, may snap into a notch 41 formed in the side thereof so as to hold the sleeve fixedly related to the handle portion until the sleeve is manually released. The shape of the aperture 36, it will be noted, is such that when the tabs 24 are positioned at the wider part thereof, as shown in Figure 1, the claws 22 will be free to approach each other to engage the impression shell 7. However, by pushing the sleeve 31 along the handle portion 11 toward the shank 12, the head 34 will be correspondingly moved to force the tabs toward the narrower end of the aperture 36. This will bring the tabs together and similarly spread the claws 22 so as to release their engagement with the impression shell. Simultaneously, the protuberance 39 will engage the notch 41 so that the claws will be held in relatively extended positions until counter-movement of the sleeve on the instrument handle portion releases them. This mechanical operation of the claws is particularly valuable when work is being done toward the rear of the mouth since it permits

one-hand manipulation of the instrument thus insuring a maximum of visibility for the operator and a minimum obstruction to illumination of the work area.

5 The method of application of the instrument is illustrated in Figure 1. Here it will be noted that the instrument is positioned above and substantially paralleling the row of teeth with the claws engaging the shell 7, which has been previously arranged on the tooth under treatment, and with the stud 18 resting on top of the immediately adjacent tooth. The handle portion 11 of the instrument is now lifted vertically, toward the dotted line position thereof indicated in Figure 1, so as to elevate the shell relative to the tooth as indicated in Figure 3. It will be further seen in Figure 3 that the oversize apertures 21 in the grip members permit the latter to retain, and to move in, a linear path, which coincides with the vertical longitudinal axis of the tooth, while the lever portion of the instrument is moving in an arcuate path. This insures that the medial or distal portions of the impression shell will not be moved laterally of the tooth during removal of the former which might cause possible distortion of the tooth impression and the production of a faulty and ill-fitting cap, jacket or inlay. It will be noted, in addition, that the portions of the claws 22 immediately adjacent the hooks 23 are bent in offset relationship with the main bodies of the grip members so that the hooks lie in the same plane transaxially of the shell. This insures that symmetrical lifting forces are applied to the opposite sides of the shell and further lessens the chances of impression distortion due to twisting or rocking of the shell relative to the tooth.

35 The instrument illustrated in Figures 1 to 3 inclusive is capable of operations on all teeth, with the exception of the rearmost molars, which have an immediately adjoining tooth rearwardly of the mouth, inability of the instrument to function in the former instance being due to the absence of a solid element behind the last tooth in the row upon which the fulcrum stud 18 may rest. However, in Figure 4, I provide an instrument which will operate on any tooth including the rearmost molars which has an adjoining tooth forwardly of the mouth. This I accomplish by providing the shank 12 with a radially extending stud 35 which is comparable to the stud 18 but which is located on the handle side of the grip members. The shank 12 is also provided with an upwardly extending angularly bent portion 39 which serves to position the handle 11 in a desirably upwardly inclined position. This upward inclination of the handle extends the range of downward swing of the latter and consequently increases the range of life of the impression shell. The positioning of the fulcrum stud forwardly of the grip members serves, of course, to permit this instrument to operate on any tooth in the mouth, provided of course that the patient has a full set of teeth, or on teeth whose position would render the instrument of Figure 2 inoperative.

60 I claim:

1. In combination with an impression sleeve provided with spaced indentations and adapted to enclose a tooth under treatment, a lever having opposed gripping elements thereon for engaging the indentations of said sleeve, and said lever having a portion thereof extended to engage an adjacent tooth to provide a fulcrum about which said lever may be moved to lift said

impression sleeve from the tooth under treatment.

2. In combination with an impression sleeve provided with spaced indentations and adapted to enclose a tooth under treatment, a lever having opposed gripping elements thereon for engaging the indentations of said sleeve, said lever having a portion thereof extended to engage an adjacent tooth to provide a fulcrum about which said lever may be moved in an arcuate path to lift said impression sleeve from the tooth under treatment, and said gripping elements during movement of said lever being moved along a linear path substantially coinciding with the vertical longitudinal axis of said tooth under treatment.

3. In combination with an impression sleeve provided with spaced indentations and adapted to enclose a tooth under treatment, a lever having opposed gripping elements thereon for engaging the indentations of said sleeve, said lever adjacent an end thereof having an integral portion thereof extended to provide a fulcrum engaging an adjacent tooth and about which said lever may be moved to lift said impression sleeve from the tooth under treatment, said gripping elements being mounted on said lever for rocking movement transversely and longitudinally thereof, and means for urging said gripping elements together to engage said impression sleeve.

4. In combination with an impression sleeve provided with spaced indentations and adapted to enclose a tooth under treatment, a lever having at one end thereof a shank provided with an extended stud for engaging an adjacent tooth to constitute a fulcrum about which said lever may be moved, a pair of gripping elements pivoted on said shank and having opposed claws for engaging the indentations of said sleeve, and means interposed between and for urging said gripping elements together to maintain engagement of said claws in said indentations.

5. In combination with an impression sleeve provided with spaced indentations and adapted to enclose a tooth under treatment, a lever having at one end thereof a shank provided with an extended stud for engaging an adjacent tooth to constitute a fulcrum about which said lever may be moved, a pair of gripping elements pivoted on said shank to move transaxially thereof and having opposed claws for engaging the indentations of said sleeve, means on a gripping element cooperative with another gripping element to limit the degree of relative transaxial movement therebetween, said gripping elements being free for pivotal movement relative to and longitudinally of said shank, and means interposed between said gripping elements for urging the claws thereof to maintain their engagement with said indentations of the impression sleeve.

6. In combination with an impression sleeve provided with spaced indentations and adapted to enclose a tooth under treatment, a lever having at one end thereof a shank provided with an angularly extending stud for engaging an adjacent tooth to constitute a fulcrum about which

said lever may be moved, a pair of wings journaled on and extending oppositely from said shank, said wings having therein enlarged apertures through which said shank passes and providing for a degree of rocking movement of said wings longitudinally of said shank, claws on said wings provided at their distal ends with hooks for engaging the indentations of said impression sleeve, one of said wings having therein an arcuate notch within which operates a pin carried by the other wing and cooperative with said pin to limit relative pivotal movement of the wings about the axis of said shank, relatively spaced tabs extending from said wings and manually engageable to move said claw hooks apart to release said impression sleeve, and a spring interposed between wings for urging said claw hooks together.

7. In combination with an impression sleeve provided with spaced indentations and adapted to enclose a tooth under treatment, a lever having at one end thereof a shank provided with an angularly extending stud for engaging an adjacent tooth to constitute a fulcrum about which said lever may be moved, a pair of wings journaled on and extending oppositely from said shank, said wings having therein enlarged apertures through which said shank passes and providing for a degree of rocking movement of said wings longitudinally of said shank, claws on said wings provided at their distal ends with hooks for engaging the indentations of said impression sleeve, tabs on and rising from said wings in spaced relative relationship, a spring interposed between said wings for urging said claw hooks together and said tabs apart, and an actuating member mounted for movement on said lever, said actuating member having a portion thereof engageable with said tabs to move said tabs toward each other and to move said claws apart.

8. In combination with an impression sleeve provided with spaced indentations and adapted to enclose a tooth under treatment, a lever having at one end thereof a shank provided with an angularly extending stud for engaging an adjacent tooth to constitute a fulcrum about which said lever may be moved, a pair of wings journaled on and extending oppositely from said shank, said wings having therein enlarged apertures through which said shank passes and providing for a degree of rocking movement of said wings longitudinally of said shank, claws on said wings provided at their distal ends with hooks for engaging the indentations of said impression sleeve, tabs on and rising from said wings in spaced relative relationship, a spring interposed between said wings for urging said claw hooks together and said tabs apart, an actuating member mounted for movement on said lever and having a portion thereof engaged with and to move said tabs toward each other upon movement of the actuating member relative to the lever, and means to releasably secure said actuating member, in one position of movement thereof, on said lever.

ALBERT E. SYKES.
